ABSTRACT OF THE DISCLOSURE

The description discloses a process which produces a high yield of carboranes from dihydrocarboranes. Upon heating a C-alkyl derivative of dihydrocarborane a C-alkyl derivative can be obtained. A high yield is obtained when the heating process is accomplished in the presence of trimethylamine.

The present invention relates to a process which produces a high yield of carboranes from dihydrocarboranes. These carboranes may be used as highly stable fuels and also are an intermediate toward a high temperature rise polymer.

The carboranes sym- $C_2B_3H_5$, unsym- $C_2B_4H_6$, sym- $C_2B_4H_6$ and $C_2B_5H_7$ have been prepared from dihydrocarborane $C_2B_4H_8$ in very low yields by the silent electric discharge process. While this process shows that carboranes can be produced from dihydrocarboranes the yield is not satisfactory for commercial utilization of the end products.

Upon seeking processes which would produce a higher yield it was thought that catalytic removal of H_2 or removal of BH_3 by a Lewis base might lead to the preparation of C-alkyl derivatives of $C_2B_4H_6$ and $C_2B_3H_5$ respectively. Since the loss of H_2 and BH_3 occurs in related boron hydrides merely by heating, a pyrolysis of dihydrocarboranes was expected to produce the carboranes $C_2B_4H_6$ and $C_2B_3H_5$.

Surprisingly, upon undertaking the pyrolysis, no alkyl derivatives of $C_2B_3H_5$ were detected and C-alkyl derivatives of $C_2B_5H_7$ were produced in an unanticipated abundance. Further, alkyl derivatives of sym- $C_2B_4H_6$ were isolated with no alkyl derivatives of unsym- $C_2B_4H_6$ being detected. Upon further search for high yield processes it was discovered that the presence of trimethylamine during the pyrolysis significantly increased the yield of sym- $C_2B_4H_6$. The carbons in the structure of both of the carboranes produced were separated which provided these products with greater stability than the dihydrocarborane wherein the carbons are adjacent one another.

Accordingly, an object of the present invention is to provide a process which will produce a high yield of stable carboranes from dihydrocarboranes.

Another object is to provide a process which will produce a high yield of C-alkyl derivatives of $C_2B_5H_7$ from $C_2B_4H_8$.

A further object is to provide a process which will produce a high yield of sym- $C_2B_4H_6$ from $C_2B_4H_8$.

A still further object is to produce new C-alkyl derivatives of carborane 2,5 and carborane 2,4.

The above stated objects as well as other objects will become readily apparent by the following description.

FIGURE 1 represents the structure of a $R_2C_2B_4H_6$ molecule;

FIG. 2 represents the structure of a $R_2C_2B_5H_5$ molecule; and

FIG. 3 represents the structure of a sym- $R_2C_2B_4H_4$ molecule.

The present invention will be more readily understood from the following examples which illustrate several embodiments thereof. All temperatures are in degrees centigrade.

EXAMPLE I

5 C,C'-dimethyldihydrocarborane-2,4, hereinafter represented as Ia was first prepared. To 10 ml. of 2,6-lutidine were added 17 mmoles of pentaborane and 30 mmoles of 2-butyne. After stirring the mixture for 5 hours at room temperature the volatile components were vacuum fractionated through traps at -80° and -190° . To the contents in the -80° trap was added 25 ml. of freshly distilled boron trifluoride ethyl etherate. After stirring the resulting heterogeneous solution for 15 minutes at room temperature the volatiles were fractionated through -20° , -80° , and -190° traps. Crude Ia which formed in the -80° trap was stored over 1 g. lithium aluminum hydride for 1 hour and then fractionated through traps at -70° and -190° . The -70° trap contained 6.9 mmoles (0.04%) of Ia.

10 One mmole of Ia was obtained and then sealed in a 25 ml. flask equipped with a 5 mm. diameter tube for taking a nuclear magnetic resonance (N.M.R.) spectra. The lowest temperature at which the disappearance of dihydrocarborane occurred at a reasonable rate was 290° . This was determined by following the H^1 N.M.R. while increasing the temperature. The minimum temperature was applied for about 20 hours until 95–100% of the Ia was decomposed. The contents of the flask were then gas chromatographed.

15 The contents were found to be approximately 25% C,C'-dimethylcarborane-2,5, hereinafter referred to as IIa, approximately 5% of C,C'-dimethyl-sym-carborane-2,4, hereinafter referred to as IIIa and byproducts of alkanes, ethane, traces of boron hydrides and possible traces of propane and butane.

EXAMPLE II

20 C-n-propyldihydrocarborane-2,4, hereinafter referred to as Ib, was first prepared. This was accomplished in the same manner as described in Example I for preparing Ia except 30 mmoles of 1-pentyne was employed in lieu of 2-butyne. The yield of purified Ib was 6.5 mmoles (38%).

25 One mmole of Ib was sealed in the 25 ml. flask and treated in the same manner as Ia was treated in Example I. The temperature was held at 300° for approximately 20 hours. The contents were approximately 30% C-n-propylcarborane-2,5, hereinafter referred to as IIb, approximate 2% C-n-propyl-sym-carborane-2,4, hereinafter referred to as IIIb and byproducts such as alkanes, propane, n-butane, traces of boron hydrides and possible traces of ethane.

EXAMPLE III

30 Ia was reacted in the flask in essentially the same manner as described for Example I except 1 mmole trimethylamine was added to the contents of the flask. The temperature was held at approximately 260° for 20 hours. Prior to the gas chromatography the trimethylamine was removed by fractionating through traps at -90° and -190° . Examination of the -190° bath indicated a nearly quantitative recovery of the trimethylamine originally present.

35 The results were approximately 15% IIa and approximately 25% IIIa, the trimethylamine being quantitatively recovered.

EXAMPLE IV

40 One mmole of Ib was reacted in the flask in essentially the same manner as described in Example II except 1 mmole of trimethylamine was added to the contents of the flask. The temperature was held at approximately 280°

for 6 hours. Prior to the gas chromatography the trimethylamine was removed through traps at -90° and -190° . As in Example III examination of the -190° bath indicated a nearly quantitative recovery of the trimethylamine originally present.

The resulting contents were approximately 15% IIb, approximately 20% IIIb, the trimethylamine being quantitatively recovered but contaminated with traces of boron hydride.

EXAMPLE V

One mmole of Ia was reacted in the flask in essentially the same manner as described in Example I except 1 mmole of isobutane was added. The temperature was kept at approximately 280° for 6 hours. After the pyrolysis the reaction mixture was introduced immediately onto the gas chromatography column for separation.

The resulting contents were approximately 30% IIa and approximately 5% IIIa. The isobutane was quantitatively recovered.

Table I is a tabulation of the results obtained in the five examples given above.

TABLE I

Ex.	Dihydro-carbo-ranes	Other material present	Minimum pyrolysis conditions		Volatile products (percent)	
			Temp., °C.	Hrs.	Carbo- ane-2,5	Sym-carbo- rane-2,4
I	Ia	None	290	20	IIa, 25	IIIa, 5.
II	Ib	do	300	20	IIb, 30	IIIb, 2.
III	Ia	(TMA)	260	20	IIa, 15	IIIa, 25.
IV	Ib	(TMA)	280	6	IIb, 15	IIIb, 20.
V	Ia	Isobutane	280	35	IIa, 30	IIIa, 5.

Nomenclature: Ia—C,C'-dimethyl-dihydrocarborane-2,4; Ib—C-n-propyl-dihydrocarborane-2,4; IIa—C,C'-dimethyl-carborane-2,5; IIb—C-n-propyl-carborane-2,5; IIIa—C,C'-dimethyl-sym-carborane-2,4; IIIb—C-n-propyl-sym-carborane-2,4; TMA—Trimethylamine.

It is to be noted that when the pyrolysis is carried out in the presence of TMA the total quantity of carbons remains substantially unchanged but that the quantity of IIIa and IIIb is greatly enhanced. When the pyrolysis is carried out in the presence of isobutane the same product distribution is obtained as when no diluent is used.

Several hypotheses appear plausible in explaining the change in distribution of the carboranes when the pyrolysis is carried out in the presence of TMA. One hypothesis is as follows:

if it is assumed that unsym- $C_2B_4H_6$, once formed, does not rearrange at 300° to the symmetrical isomer then the following hypothesis is a possible explanation:

The presence of TMA might catalyze the first two reactions in both hypotheses and yet not appreciably affect the third reaction in each since the catalysis in the third reactions would involve a three-body collision.

The structures of the compounds were confirmed by B^{11} nuclear magnetic resonance (N.M.R.) tests. It was determined that Ia and Ib structurally resemble a pentagonal pyramid, as shown in FIG. 1, that IIa and IIb structurally resemble a trigonal bipyramidal, as shown in FIG. 2, and that IIIa and IIIb structurally resemble an octahedron, as shown in FIG. 3. It is to be noted that the separation of the carbons in FIGS. 2 and 3 result in a more thermodynamically molecular species of the II and III series than where the carbons are adjacent one another.

The alkane side products produced during the pyrolysis

indicate that the skeletal carbon—carbon bond is rather easily broken. It is to be noted that n-butane is formed from the pyrolysis of Ib, however, no pentane is found. Further, a considerable amount of propane is formed in addition to n-butane, and yet none of the parent (non-alkylated) carboranes are formed in the process. It is probable that the dihydrocarboranes and/or carborane radicals lead to these side products.

Table 2 below shows the physical data for the carboranes and the dihydrocarboranes, in the above examples:

TABLE 2.—PHYSICAL DATA FOR THE CARBORANES AND DIHYDROCARBORANES

15	Compound	Gas chromatography; R _v	Mass Spectrum; observed parent peak	Melting Point
Ia		2.2	104	-64--63
Ib		6.2	(¹)	(²)
IIa		1.9	114	-30--28
IIb		5.4	128	-99--97
IIIa		1.1	102	-2--1
IIIb		2.4	116	-88--87

¹ Not taken.

² Glass.

25 The melting points are in good relative agreement with the symmetry of the structures of the dihydrocarboranes-2,4, sym-carborane-2,4 and carborane-2,5. The series Ia, IIa, IIIa and the series Ib, IIb, and IIIb represent a progression to greater symmetry and, therefore, one would expect the increase in the melting point. The *a* compounds containing methyl substitutes on each of the two skeletal carbons melt at a higher temperature than the *b* compounds with a propyl group on only one of the skeletal carbons.

30 It is now readily apparent that the present invention provides processes which produce a high yield of carboranes from dihydrocarboranes. By a pyrolysis of dihydrocarboranes a high yield of C-alkyl derivatives of $C_2B_5H_7$ are produced and when the pyrolysis is carried on in the presence of TMA a high yield of sym- $C_2B_4H_6$ is obtained. By a separation of the carbons in the structure the products will be more stable than the dihydrocarborane.

35 Obviously many modifications and variations of the present invention are possible in the light of the above teachings. It is therefore to be understood that within the scope of the appended claims the invention may be practiced otherwise than as specifically described.

- What is claimed is:
1. C,C'-dimethylcarborane-2,5, $C_4B_5H_{11}$.
  2. C-n-propylcarborane-2,5, $C_5B_5H_{13}$.
  3. C,C'-dimethyl-sym-carborane-2,4, $C_4B_4H_{10}$.
  4. C-n-propyl-sym-carborane-2,4, $C_5B_4H_{12}$.
  5. A process for preparing C-methyl derivatives of 4-boron carboranes and 5-boron carboranes comprising the steps of:
    - (a) heating a C-methyl derivative of a 4-boron dihydrocarborane until the C-methyl derivatives of said carboranes are formed and
    - (b) recovering said C-methyl derivatives of said carboranes.
  6. A process as claimed in claim 5 wherein:
    - (a) said heating of the C-methyl derivative of said 4-boron dihydrocarborane is conducted in a temperature range of 250-300 degrees centigrade.
  7. A process as claimed in claim 5 wherein:
    - (a) said heating of the C-propyl derivative of said 4-boron dihydrocarborane is conducted in a temperature range of 250-300 degrees centigrade.
  8. A process for preparing C-methyl derivatives of carboranes comprising the steps of:
    - (a) reacting pentaborane with butyne in the presence of lutidine to obtain a C-methyl derivative of a 4-boron dihydrocarborane;

(b) heating the dihydrocarborane in the presence of trimethylamine until the carboranes are formed; and
 (c) recovering the carboranes thus formed.

9. A process for preparing C,C'-dimethylcarborane-2,5 and C,C'-dimethyl-sym-carborane-2,4 comprising the steps of:

(a) heating C,C'-dimethyldihydrocarborane-2,4 at a temperature between 250° C. and 300° C. until the 4-boron carboranes and 5-boron carboranes are formed and

(b) recovering said carboranes thus formed.

10. A process as claimed in claim 9 including the step of:

(a) heating the C,C'-dimethyldihydrocarborane-2,4 in the presence of trimethylamine.

11. A process for preparing C-n-propylcarborane-2,5 and C-n-propyl-sym-carborane-2,4 comprising the steps of:

(a) heating C-n-propylmethyldihydrocarborane-2,4 at a temperature between 250° C. and 300° C. until 4-boron carboranes and 5-boron carboranes are formed and

(b) recovering said carboranes thus formed.

12. A process as claimed in claim 11 including the step of:

(a) heating the C-n-propylmethyldihydrocarborane-2,4 in the presence of trimethylamine.

13. A process for preparing C-propyl derivatives of 4-boron and 5-boron carboranes comprising the steps of: heating a C-propyl derivative of a 4-boron dihydrocarborane until the C-propyl derivatives of said carboranes are formed; and recovering said C-propyl derivatives of said carboranes.
